UNITED STATES PATENT OFFICE

170,833

BIRDHOUSE

Stephen F. Rebora, Chicago, Ill.

Application August 31, 1953, Serial No. 26,638

Term of patent 14 years

(Cl. D31—2)

To all whom it may concern:

Be it known that I, Stephen F. Rebora, a citizen of the United States and a resident of Chicago, in the county of Cook and State of Illinois, have invented a new, original, and ornamental Design for a Birdhouse, of which the following is a specification, reference being had to the accompanying drawing, forming a part hereof.

In the drawing:

Figure 1 is a perspective view of a birdhouse showing my new design;

Fig. 2 is a side elevational view, both sides being alike; and

Fig. 3 is a front view of the birdhouse, the front and rear views being alike except that the

front contains the large, round door opening while in the rear there is only the small, round opening appearing at the center of the front door opening.

I claim:

The ornamental design for a birdhouse, as shown and described.

STEPHEN F. REBORA.
